UNITED STATES PATENT OFFICE.

ALBERT N. NORRIS, OF RUSHVILLE, INDIANA.

IMPROVEMENT IN GRAIN-DRILLS.

Specification forming part of Letters Patent No. **149,674**, dated April 14, 1874; application filed August 21, 1873.

To all whom it may concern:

Be it known that I, ALBERT N. NORRIS, of Rushville, Indiana, have invented a new and useful Improvement in Grain-Drills; and I do hereby declare that the following is a full, clear, and exact description thereof, reference being had to the accompanying drawings and to the letters of reference marked thereon.

Figure 1 represents a top view of framework of a seed-drill and its connecting mechanism. Fig. 2 represents a rear view of the boxing for the gearing, by which the feeding apparatus is operated. Fig. 3 represents a horizontal section of the parts exhibited in Fig. 2. Figs. 4, 5, and 6 represent detached parts of the gear-boxing exhibited in Figs. 2 and 3, and at H in Fig. 1.

A is the center bar of the frame, having the driving-wheel B, with its axle boxed at C, which carries beveled gear D, to work with gear E on shaft N', which enters that of gear J, through which shaft and its connections the feed apparatus is operated. O O are pivoted or hinged bars, linked together adjustably at V V U. The seed-boxes S G R are located upon the bars O O A, and the gear-shafts P' F connect the gears Y Z J with the feeding apparatus. The gear K is an intermediate or idler, used to give proper direction to the revolutions of gear Z. This gearing (shown in Fig. 3) operates the feed apparatus; and as it is necessary to adjust the hose-bars O O of the seed-drill laterally to vary the width of the rows, provision has been made for a like adjustment of the several feeding devices which discharge the feed. My invention is designed to effect this purpose, and consists in making the boxing of the central gears Y Z J K in several parts, so that the pinions or gears Y Z may be adjusted horizontally with their pivoted boxing M, while still meshing with their adjoining gears J K, and thereby permit the lateral

adjustment of the pivoted bars O O with their respective hoes, seed-boxes, and shafts P P. Shafts P P occupy the hubs, as seen at X' X', of the adjustable gears Y Z. The central portion of the gear-boxing may be cast in two pieces, H H', with a horizontal division, as seen in Figs. 4 and 5, and lugs L L are cast thereon for the journals e e of the adjustable boxing M, in which the gears Y Z have their hubs journaled, as shown at S S, Fig. 2. The cogs of the gears J K Y Z should be made beveling longitudinally, so that they will remain in mesh when the position of the latter two is changed by the lateral adjustment of the side bars O O, and shafting P P thereon.

It will be understood that the feed-boxes are operated through the shafts P, P, F, and N', and the above-named gearing.

The reason for making the boxing H H' and M M in divisions, as denoted by the line X" X", is to facilitate the casting operation, and admit the gear-hubs or journals into their respective boxes.

The curved or angular support T serves as a guide, upon which the adjustable bars O O slide when adjusted laterally for the purpose specified. It is evident that the face of the gear-cogs may be made in the arc of a circle or oval instead of beveling, as stated above, and retain their connection or mesh with each other when adjusted, as described.

I claim as my invention—

The sectional case H H', with pivoted bearings M M, and inclosed gears J K Y Z, constructed and arranged substantially as and for the purpose described.

Witness my hand this 6th day of August, A. D. 1873.

ALBERT N. NORRIS.
